UNITED STATES PATENT OFFICE.

ERNEST W. HUTTIG, OF PITTSBURGH, PENNSYLVANIA, ASSIGNOR TO GILL BROTHERS COMPANY, OF STEUBENVILLE, OHIO, A CORPORATION OF WEST VIRGINIA.

DESIGN FOR A GOTHIC SHADE-BOWL.

50,065.

Specification for Design.

Patented Dec. 19, 1916.

Application filed September 20, 1916. Serial No. 121,322. Term of patent 7 years.

To all whom it may concern:

Be it known that I, ERNEST W. HUTTIG, a citizen of the United States of America, and resident of Pittsburgh, county of Allegheny, State of Pennsylvania, have invented a certain new, original, and ornamental Design for a Gothic Shade-Bowl, of which the following is a specification.

In the accompanying drawing, which is a perspective view taken from the side, I have illustrated a shade bowl constructed in accordance with my invention.

The device consists of a short cylindrical portion 1, closed at the bottom by a convex

portion 2, the cylindrical portion being ornamented with a Gothic design as shown.

Having thus described and illustrated my invention, I claim:

The ornamental design for a Gothic shade bowl, substantially as shown and described.

Signed by me at Pittsburgh, county of Allegheny, State of Pennsylvania, this 15th day of September, 1916.

ERNEST W. HUTTIG.
